UNITED STATES PATENT OFFICE.

JAMES COIA, OF RAVENNA, OHIO.

TIME-CONTROLLED MECHANISM FOR GRAPHOPHONES.

1,375,279.

Specification of Letters Patent. Patented Apr. 19, 1921.

Application filed May 6, 1920. Serial No. 379,238.

To all whom it may concern:

Be it known that I, JAMES COIA, a subject of the King of Italy, residing at Ravenna, in the county of Portage and State 5 of Ohio, have invented certain new and useful Improvements in Time-Controlled Mechanism for Graphophones, of which the following is a specification.

My invention relates to time controlled 10 means for operating a graphophone or the like.

An important object of the invention is to provide means of the above mentioned character, embodying a clock, which may be 15 bodily removed for winding or adjustment, or which may be wound or adjusted in place, without the employment of the usual connecting rods or elements, connected with the operating parts of the clock, and extending 20 to convenient positions exteriorly of the casing of the graphophone.

A further object of the invention is to so correlate the time controlled mechanism and the operating parts of the graphophone, that 25 the elements thereof coöperate in a novel manner, producing a construction which is simple, inexpensive and easy to operate.

Other objects and advantages of the invention will be apparent during the course 30 of the following description.

In the accompanying drawings forming a part of this specification and in which like numerals are employed to designate like parts throughout the same,

35 Figure 1 is a plan view of a graphophone embodying my invention,

Fig. 2 is an enlarged plan view of the stop or brake mechanism,

Fig. 3 is a horizontal section taken on line 40 3—3 of Fig. 5, looking up,

Fig. 4 is a longitudinal section taken on line 4—4 of Fig. 3, parts in elevation,

Fig. 5 is a front elevation of a graphophone,

45 Fig. 6 is a vertical section taken on line 6—6 of Fig. 5,

Fig. 7 is an inner end elevation of a clock, Fig. 8 is a perspective view of the key of the clock,

50 Fig. 9 is a perspective view of a clamp, and

Fig. 10 is a fragmentary side elevation of an arm included in the device.

In the drawings, wherein for the purpose 55 of illustration is shown a preferred embodiment of my invention, the numeral 10 design-

nates a body portion or casing of a graphophone, having a top 11, to which is secured a casing 12 of a spring motor, embodying a vertical shaft 13, supporting and rotating a 60 table 14, upon the top of the casing. The numeral 15 designates the sound-box, carrying the usual needle to engage with the record, and this sound-box may be connected with the usual swinging tubular arm 16, discharging into the casing 10, or the sound-box may be connected with a horn, as is 65 well known.

The front side 17 of the casing has a centrally arranged opening 18, which is preferably circular, for the reception of a casing 19, preferably circular, of a clock or time controlled mechanism. This casing 19 is provided with an annular rib 20, upon its periphery, which rib is preferably curved 75 in cross section. The rib is arranged adjacent the rear end of the opening 18, and contacts with the inner wall of the front side 17, for completely closing the opening 18.

The clock or clock casing 19 is detachably 80 held within the opening 18 by means of clamps 21, having curved contact faces, to engage the rib 20. I preferably employ two of these clamps 21, and screw-threaded bolts 22 have swiveled connections with the 85 clamps, and these bolts are screw-threaded within apertured lugs 23, formed upon strips 24. These strips are rigidly attached to the inner side of the member 17. In order that access may be readily had to the bolts 90 22, for turning them, and to the clock casing, to remove it, or to adjust the clock, the side of the casing 10 at a right angle to the clock is open, and is adapted to be covered by a swinging door 25, hinged at 26, and provided with a knob 27, for opening and closing. This door may be employed to regulate the volume of sound passing from the casing 10.

As shown in Fig. 5, the clock embodies 100 a dial 28, provided with characters for indicating the hours, together with the usual hands 29, and a small hand 30, which may be turned by a shaft 31, to set the alarm for operation at a selected time, as is well 105 known. The alarm means embodies the usual spring-winding key 32, which is rotated in one direction to wind up the spring and turns in an opposite direction when the alarm mechanism is operating or unwinding. The key 32 embodies apertured ears 33, and an extension 34, projecting out-

wardly beyond the same, such extension serving as a drum, upon which a flexible element, to be described, is wound. By the term "alarm mechanism" is meant the usual 5 spring operated means found in the ordinary alarm clock, for operating an alarm at a selected time, but I may employ this mechanism with or without the gong and hammer, as I may prefer to start the graphophone without the sounding of a bell or gong, and the term is intended to cover such mechanism, with or without the sound producing means.

The stop or brake mechanism embodies a 15 base 35, secured to the top 10 by screws 36 or the like. A table 37 is pivoted upon the base 35, as shown at 38, and carries an inner arm 39, provided with a socket 40, receiving fibrous material 41, to contact with the edge 20 or periphery of the rotatable table 14. The table 37 carries an outer arm 42, the outer end of which is preferably bent upwardly, while the arm 39 is preferably straight. The upwardly offset portion 43 of the arm 42 is 25 arranged in the plane above the arm 39. The base 35 has an extension 44, having connection with a retractile coil spring 45, secured to an ear 46, carried by the arm 42. When the lever 39 is shifted to the inner 30 position to hold the rotatable table against movement, the spring 45 is shifted to the right of the pivot 38, or past dead center, and hence will hold the brake element in the said position. When the brake element is 35 swung in the direction of the arrow, for a slight distance, the spring 45 is shifted upon the opposite side of the pivot 38, and quickly completes the shifting movement of the brake element, and retains it open.

40 The arm 42 of the brake element is adapted to be started in its shifting movement by a vertically adjustable pin 47 (see Fig. 4) which is arranged behind this lever when the brake element is set, as shown in Fig. 1. 45 The pin 47 is screw-threaded and engages within a screw-threaded apertured head 48, formed upon a reciprocatory rod 49. The pin 47 travels in a slot 50. The pin 47 may also serve as a stop for the arm 39, when the 50 brake element is being swung to the open position.

The rod 49 is arranged beneath the top 11 and slides within apertured brackets 51, secured to the top. The rod 49 is shifted forwardly in the direction of the arrow, by a compressible coil spring 52, surrounding the rod, and engaging an element 53, rigidly attached to the rod. To the rear end of the rod 49 is secured a flexible element or cable 60 54, passed about pulleys 55 and 56. The cable is then passed about a horizontal pulley 57, rotatably held within a frame 58, secured to the top 10. The cable then extends to the element 34, upon which it is to be wound 65 and is provided at its free end with a

hook 59, to detachably engage within either ear 33.

The operation of the apparatus is as follows:

With the clock in place, the operator may 70 pass his hand through the open side of the casing, and connect the hook 59 in the ear 53. The key 32 is now turned to wind up the spring of the alarm mechanism, which at the same time winds the cable upon the element 75 34. This winding of the cable draws the rod 49 rearwardly, and places spring 52 under tension. The pin 47 may now be in the elevated position, and the brake element may now be swung to the closed position, for 80 holding the table against rotation. At the proper time, the time controlled mechanism will rotate the key 32 in an opposite direction to unwind the cable 54, the spring 52 then shifting the rod 49 to the left, Fig. 4. 85 The pin 47 will contact with the arm 42, and swing the brake element to the open or release position, whereby the spring motor will rotate the table 14. The pin 47 being in advance of the arm 39, will function as a 90 stop for the arm, upon its outward movement. Should it be desired to use the brake element, independently of the time controlled means, the pin 47 is rotated to lower it, beneath the upwardly offset end 43 of the 95 arm 42, but this pin will still serve as a stop for arm 39. The brake element may now be turned to the left, and employed to hold the table against rotation, and manually operated, to release it, as may be desired.

100 It is to be understood that the form of my invention herewith shown and described is to be taken as a preferred example of the same, and that various changes in the shape, size, and arrangement of parts may be resorted to without departing from the spirit of my invention, or the scope of the subjoined claims.

Having thus described my invention, I 110 claim:

1. In apparatus of the character described, the combination with the casing and rotatable table of a sound reproducing machine, of a brake element to engage the rotatable table and hold it against movement including a movable element, a longitudinally movable rod arranged within the casing, yielding means to move the rod in one direction, means for controlling the movement of the rod by the yielding means, and a vertically adjustable element connected with the rod to engage with the movable element.

2. In apparatus of the character described, the combination with the casing and 125 rotatable table of a sound reproducing machine, of a brake element pivoted to the casing to engage and disengage the table, a longitudinally movable rod arranged within the casing, yielding means to move the 130

rod in one direction, means to control the movement of the rod by the yielding means, yielding means to hold the brake element in positions to engage and disengage the table, 5 and a vertically adjustable element connected with the rod and arranged to engage the brake element.

3. In apparatus of the character described, a pivoted brake element to engage 10 and disengage the rotatable table of a sound reproducing machine, a spring connected with the pivoted brake element to move the same in the closed and open position, said spring being adapted to be shifted upon opposite 15 sides of said pivot, a longitudinally movable rod, yielding means to move the rod in one direction, means to control the movement of the rod by the yielding means, and a vertically adjustable pin connected 20 with the rod and adapted to engage with a portion of the pivoted brake element.

4. In apparatus of the character described, a pivoted brake element embodying an inner arm arranged substantially horizontally 25 and having an element to contact with the rotatable table of the sound reproducing machine, and an outer arm having a portion thereof offset upwardly to be arranged in a horizontal plane above the inner arm, a spring connected with the brake element and adapted to hold it in the inner and outer positions, said spring being adapted to be shifted upon opposite sides of 30 the pivot, a longitudinally movable rod, means to move the rod in one direction, and a vertically adjustable pin carried by the rod, said pin being adapted to engage with the outer arm when suitably elevated. 35

5. In apparatus of the character described, a pivoted brake element embodying 40 an inner arm carrying an element to contact with the rotatable table of a sound reproducing machine and an outer arm having a portion thereof offset upwardly above the inner arm, a spring connected with the pivoted brake element and adapted to hold it in the inner and outer positions, said spring being adapted to be shifted upon opposite sides of the pivot, a movable member, means to move the member, and a vertically adjustable pin carried by the member and adapted to engage the upwardly offset portion of the outer arm when the pin is elevated and also serving as a stop for the inner arm. 55

6. In apparatus of the character described, the combination with the rotatable table of a sound reproducing machine and the support for the table, of a brake element to control the rotation of the table and 60 including a movable element, a bodily shiftable member, automatic means to move the member in one direction, means for controlling the movement of the member by the automatic means, and an element connected with the bodily movable member and adapted to be adjusted laterally with relation thereto into and out of the path of travel of said movable element. 65

In testimony whereof I affix my signature in presence of two witnesses. 70
